DROP WIRE TIE

Wesley A. Daniels, Chaumont, N. Y.

Application March 11, 1949, Serial No. 80,988

8 Claims. (Cl. 24—115)

1

The present invention relates to anchor connectors for drop wires or service wires and the like. Such anchor connectors are commonly referred to in the trade as drop wire ties, and are extensively used to attach electrical conductors such as telephone, lighting and other wires, to buildings, poles, and other structures.

The anchor connector of the present application has evolved in the course of my developments and improvements of a prior connector which was patented by me jointly with others as Patent No. 2,345,890, granted April 4, 1944, and of another improved connector which is the subject of pending application Serial No. 775,112, filed September 19, 1947, now abandoned. This invention which I will hereinafter more fully describe, embodies certain basic features of the prior constructions just referred to, but these basic features are organized in a new and improved relationship, and have been still further modified and improved so as to attain even more superior results, as compared with either the antecedent constructions herein referred to, or with the prior art generally, including those drop wire ties now most commonly used in the attachment of drop wires or service wires to poles, buildings, and similar structures.

The present invention has for its primary objectives the provision of an effective anchor connector of simple and inexpensive form, and producing the combined effects of both frictional or snubbing action on a wire, as well as a positive gripping action, which actions are mutually interrelated so as to increase the effectiveness of each other.

A further object of the invention is to provide an anchor connector of the aforementioned type, which is strong and durable, easy to install, and which expedites its engagement with the wire to be anchored, or disengagement of the wire therefrom.

A still further object of the invention is to provide an anchor connector or drop wire tie which includes an endless-loop frame of wire or other equivalent material, having a bail at one end for attachment to a support, a plurality of rigidly interconnected snubbing members pivotally and slidably carried by the frame and normally bridging across the frame when anchoring a wire, while being free to swing to a position spacing the snubbing members from the frame to permit a wire to be more readily engaged with or disengaged from the snubbing members, without interruption or severing of the wire, and a clamping member slidably mounted on the frame and

2

freely movable towards and away from the snubbing members, but having means positively restraining the clamping member against movement relative to the snubbing members when the latter assume their normal wire-anchoring positions in use.

Other and further objects and advantages of the invention will be hereinafter described and the novel features thereof defined in the appended claims.

In the drawing:

Figure 1 is a view in perspective of a drop wire tie or anchor connector constructed according to the present invention, with the snubbing members swung open or away from the frame of the connector device so as to facilitate engagement of a wire with the snubbing members, the wire also being shown in this view entwined or interlaced about the snubbing members as in a typical installation, but preliminary to closing of the snubbing members against the frame to assume its normal wire-anchoring position on completion of the installation and anchorage of the wire;

Figure 2 is a top plan view of the drop wire tie or connector device as seen in a completed installation, with the snubbing members closed against the frame of the device, and the wire entering the device at one end and passing continuously about the snubbing members in interlaced or entwined relation thereto, and finally passing downwardly at the other end of the device between the last snubbing member and an auxiliary clamping member which positively clamps the wire at the latter end of the device;

Figure 3 is a fragmentary view in side elevation of the assembly shown in Figure 2, but on a somewhat enlarged scale, with the bail end of the device broken away, and with the wire shown in the final anchored position;

Figure 4 is a longitudinal sectional view taken centrally through the drop wire tie on the line 4—4 of Figure 2, with the wire shown in elevation;

Figure 5 is a transverse sectional view taken on the line 5—5 of Figure 2, looking in the direction of the arrows;

Figure 6 is a transverse sectional view taken on the line 6—6 of Figure 2, looking in the direction of the arrows; and

Figure 7 is an enlarged perspective view showing the details of the auxiliary clamping member which is located towards the bail end of the anchor connector device.

Like reference characters designate corre-

55

sponding parts in the several figures of the drawing, wherein 1 generally denotes a frame having the form of an endless loop of generally elongated and rectangular outline. This frame may be made of relatively stiff wire or other suitable material. As best seen in Figures 1 and 2, the opposite sides of the frame are arranged in parallel and laterally spaced relation to each other, as indicated at 2, 2, and these sides constitute arms or bars of substantial length which are joined together at one end by a transversely extended bar 3, and at the other end by a more or less rounded bail 4 which is adapted to be engaged with a suitable hook or other fastening member on a pole, building, or other structure, not shown, to which the wire to be anchored is to be attached. As shown in the drawing, the frame may be made of a continuous single piece of wire or other material which is bent in any suitable manner into the form just described, with the free ends of the wire overlapped upon each other and soldered, welded, or otherwise suitably secured together, as indicated at 2'. Instead of overlapping the adjoining ends of the wire frame, the ends may be butted together and suitably connected to each other, as by means of a clamping sleeve or collar such as is well-known in the art, and hence need not be further illustrated or described.

Mounted on the frame 1 is a plurality of rigidly interconnected snubbing members preferably having the form of an elongated snubbing unit as indicated at 5, and a separate auxiliary clamping member, generally indicated at 5'. As shown, the snubbing unit 5 is preferably made in one piece, and may be formed of metal or other appropriate rigid and durable material of adequate strength, sufficient to sustain the stresses and strains imposed thereon when in use to anchor a wire such as a telephone, light or other service wire.

The snubbing unit 5 is provided at one edge thereof with a longitudinally extended flat bar 6, and projecting laterally from one edge of the bar 6 is a plurality of equidistantly spaced snubbing posts or projections designated 7 which are extended from the bar 6 so as to be of such length as to bridge the gap or space between the arms or bars 2, 2 of the frame 1, when the snubbing members 7 assume a position as more particularly shown in Figure 2. The extreme opposite ends of the flat bar 6 are bent at right angles to the plane of this bar, as indicated at 8, 8, forming ears or lugs which are suitably apertured so as to loosely receive one of the arms 2 therethrough. Thus, the snubbing unit 5 is freely slideable on one of the arms 2 of the wire frame 1, and is also freely pivotal on this arm so that the snubbing posts may be swung upwardly to an open or spaced position with respect to the other arm 2 of the wire frame 1, as shown in Figure 1. When in this open or upwardly shifted position, the wire to be anchored may be more readily and quickly engaged with the snubbing posts or projections 7 in an interlaced or entwined relation thereto, as illustrated in Figure 1 in which the wire to be anchored is designated 9.

It will also be observed from the drawing that the free or outer end of the post 7 which is nearest to the end of the anchor device at which the wire 9 enters the anchor device, is extended longitudinally, as indicated at 10, in parallel relation to the flat bar 6, and this extension 10 terminates in a laterally offset ear or lug 11 which

is notched out, as at 12, so as to permit the snubbing unit 5 to be swung or pivoted to a closed position, as illustrated in Figure 2, with the extension 10 and the tips of the snubbing posts or projections 7 resting flat upon the arm or bar 2 of the wire frame 1 which is spaced from the arm of the frame on which the snubbing unit is pivotally and slidably mounted. The extension 10 thus forms with the flat bar or base 6 of the snubbing unit 5 a longitudinally extended slot or gap 13 at the wire-entering end of the anchor device, and thus aids in maintaining the wire to be anchored in a more or less central position when it is entwined about the snubbing posts or members 7, thus minimizing likelihood of displacement of the wire from the snubbing posts during and after the anchorage of the wire.

At the other end of the snubbing unit 5, the auxiliary clamping unit 5' is arranged to positively grip the wire 9 at the point where it passes downwardly and leaves the anchor connector or drop wire tie. This auxiliary clamping member 5' is shown as having the form of a transversely extended flat bar 14 provided at its opposite ends with upwardly extended ears 15, 15 arranged perpendicularly to the bar 14, and being suitably apertured to loosely receive the arms 2, 2 of the wire frame 1 therethrough, so that the bar 14 is freely slideable on the arms 2, 2. At that end of the bar 14 which is slideable on the arm 2 opposite to the other arm 2 on which the snubbing unit 5 is pivotally and slidably mounted, the bar 14 is extended longitudinally of the arm 2, as indicated at 16, and terminates in an upwardly extended lug or ear 17 which is notched, as at 18, to slidably receive the bar 2 therethrough. The slotted ear or lug 17 which is in spaced relation to but aligned with one of the lugs or ears 15 at the same end of the bar 14, serves to prevent the bar 14 from becoming cocked across the wire frame 1, thereby minimizing interference with free sliding movement of the bar 14 towards and away from the adjacent end of the snubbing unit 5. The bar 14 serves to prevent undue spreading or constriction of the bail end of the frame 1, while the member 10 with the notched out lug 11 when closed down upon the wire frame in the position shown in Figure 2, assist the transverse bar or arm 3 of the frame 1 in preventing constriction or mashing together of the opposite sides of the frame 1.

When the bar 14 is moved towards the adjacent end of the snubbing unit 5 until it tightly clamps the wire 9 against the last snubbing member 7 at the point where the wire 9 leaves the anchor connector and drops downwardly, the ear 17 which is rigidly connected with the bar 14 engages behind the post 7 so as to positively restrain the bar 14 against movement away from the snubbing member 5, thereby continuously maintaining the clamping action upon the wire 9 so long as the ear 17 is interlocked behind the member 7, as best shown in Figures 2 and 3. In order to effect such interlocking engagement, the bar 14 must be forced up tightly against the wire 9 before the snubbing unit 5 is swung to its fully closed position, so that the rearmost snubbing post 7 will move into interlocking engagement with the ear 17 as the snubbing unit 5 approaches its fully closed position with the tips of all of the snubbing posts 7 resting flat against the corresponding side of the wire frame 1.

The operation and installation of the anchor connector or drop wire tie device will be readily apparent to those skilled in the art, and may be

briefly summarized as follows. The anchor device may be applied to or engaged with a wire at any desired point along its length and without interrupting or cutting the wire at the point of anchorage, by first swinging the snubbing unit 5 to an open or upwardly shifted position as illustrated in Figure 1. While in this position, the wire, such as the wire 9, is passed upwardly through the frame 1, so that the wire leads into the anchor connector beneath the transversely extended bar 3 of the frame 1, then through the slot 13, after which it is alternately passed about the snubbing posts or projections 7 in the manner illustrated in Figure 1. At the opposite end of the snubbing unit 5, the wire 9 is passed downwardly between the last snubbing post 7 and the transverse bar 14, and the latter bar is pulled up tight against the wire as the snubbing unit 5 is swung downwardly to a closed position, so that the last snubbing post will become interlocked with the lug 11 of the bar 14 as the snubbing unit approaches its fully closed position. The wire 9 is then tightly and firmly secured to the drop wire tie or anchor device, and the bail 4 of the frame 1 may then be secured by a hook or other suitable fastening to a pole or other structure to which the wire 9 is to be anchored. When the wire has been so installed, the greater the strain or the harder the pull on the wire, the greater the friction on the wire by the snubbing members 7, and the greater resistance to relative pivotal movement of the rearmost snubbing post 7 with respect to the clamping bar 14, and consequently the greater resistance to slippage of the wire relative to the anchor connector or drop wire tie device. Due to the weight of the wire itself, together with the strain thereon when it is anchored, there is no likelihood of movement of the snubbing unit 5 towards an open position or release of the snubbing and clamping actions on the wire, and I have found that my new drop wire tie is fully effective and satisfactory under all conditions normally encountered in ordinary service, and is far superior to drop wire ties of conventional construction.

It will be obvious from the foregoing that the wire 9 may be quickly and easily removed or disengaged from the drop wire tie device by first lifting or swinging the snubbing unit 5 in an upward direction to disengage the lug 11 therefrom and permit sliding of the bar 14 in a direction tending to release the clamping pressure on the wire, after which the wire may be displaced from the snubbing members 7, all without interruption or severing of the wire.

In the case where the snubbing unit 5 and the clamping bar 14 are made of metal, those parts thereof which come into engagement with the wire when anchored may be suitably insulated, as by covering the parts with rubber or other insulating material, but I have found that this is not absolutely essential, since the device functions with a minimum of chafing action or other likelihood of damage to the usual insulation on the wire 9 itself. In lieu of making the parts of metal, they may be made of hard rubber, fiber, plastic, glass, porcelain, "Bakelite," or other similar material of adequate strength when suitably proportioned, and which have insulating properties, although the latter are not essential. Preferably all corners of the device which come into contact with the wire 9 are rounded or smoothed so as to minimize the likelihood of damage to the wire, although even this is not absolutely essential.

While the specific details have been herein shown and described, the invention is not confined thereto as changes and alterations may be made without departing from the spirit thereof as defined by the appended claims.

I claim:

1. An anchor connector of the class described, comprising a frame, multiple wire snubbing means mounted on said frame for snubbing engagement with a wire to be anchored, said snubbing means having the form of a longitudinally extended, substantially rigid, unit having a plurality of snubbing members transversely extended therefrom in equidistantly spaced relation to each other, and wire clamping means also mounted on said frame at one end of said snubbing means, said snubbing means and clamping means being relatively movable on said frame towards and away from each other and being adapted to receive the wire therebetween for clamping engagement therewith.
2. An anchor connector of the class described, comprising a frame having laterally spaced, parallel sides, multiple wire snubbing means mounted on said frame for snubbing engagement with a wire to be anchored, said snubbing means having the form of a longitudinally extended, substantially rigid, unit having a plurality of snubbing members transversely extended therefrom in equidistantly spaced relation to each other, the opposite ends of the snubbing unit aforesaid being offset at a right angle to the longitudinal axis of the unit, and being apertured to loosely receive one of the parallel sides of the frame therethrough, whereby to permit both sliding and pivotal movements of the snubbing unit relative to the frame, and wire clamping means also mounted on said frame at one end of said snubbing means, said snubbing means and clamping means being relatively movable on said frame towards and away from each other and being adapted to receive the wire therebetween for clamping engagement therewith.
3. An anchor connector of the class described, comprising a frame having laterally spaced, parallel sides, multiple wire snubbing means mounted on said frame for snubbing engagement with a wire to be anchored, said snubbing means having the form of a longitudinally extended, substantially rigid, unit having a plurality of snubbing members transversely extended therefrom in equidistantly spaced relation to each other, the opposite ends of the snubbing unit aforesaid being offset at a right angle to the longitudinal axis of the unit, and being apertured to loosely receive one of the parallel sides of the frame therethrough, whereby to permit both sliding and pivotal movements of the snubbing unit relative to the frame, the free ends of the spaced snubbing members normally resting upon the other parallel side of the frame when the wire to be anchored has been alternately interlaced about the snubbing members, but said free ends of said snubbing members being movable towards and away from the latter side of the frame responsive to pivotal movement of the snubbing unit on the opposite side of the frame, and wire clamping means also mounted on said frame at one end of said snubbing means, said snubbing means and clamping means being relatively movable on said frame towards and away from each other and being adapted to receive the wire therebetween for clamping engagement therewith.
4. An anchor connector of the class described,

comprising a frame having laterally spaced, parallel sides, multiple wire snubbing means mounted on said frame for snubbing engagement with a wire to be anchored, said snubbing means having the form of a longitudinally extended, substantially rigid, unit having a plurality of snubbing members transversely extended therefrom in equidistantly spaced relation to each other, and wire clamping means also mounted on said frame at one end of said snubbing means, said clamping means having the form of a transversely extended clamping bar having its opposite ends offset at a right angle thereto and being apertured to loosely receive the respective parallel sides of the frame therethrough, whereby to permit sliding movement of the clamping means relative to the frame and to the snubbing means, said clamping means and snubbing means being adapted to receive the wire therebetween for clamping engagement therewith.

5. An anchor connector of the class described, comprising a frame having laterally spaced, parallel sides, multiple wire snubbing means mounted on said frame for snubbing engagement with a wire to be anchored, said snubbing means having the form of a longitudinally extended, substantially rigid, unit having a plurality of snubbing members transversely extended therefrom in equidistantly spaced relation to each other, and wire clamping means also mounted on said frame at one end of said snubbing means, said clamping means having the form of a transversely extended clamping bar having its opposite ends offset at a right angle thereto and being apertured to loosely receive the respective parallel sides of the frame therethrough, whereby to permit sliding movement of the clamping means relative to the frame and to the snubbing means, said clamping means and snubbing means being adapted to receive the wire therebetween for clamping engagement therewith, one end of said clamping bar being extended for interlocking engagement with one of the snubbing members of the snubbing means when in its wire-clamping position.

6. An anchor connector of the class described, comprising a frame, wire snubbing means mounted on said frame for snubbing engagement with a wire to be anchored, and wire clamping means also mounted on said frame at one end of said snubbing means, said snubbing means and clamping means being relatively movable on said frame towards and away from each other and being adapted to receive the wire therebetween for clamping engagement therewith, and means

10 for interlocking the clamping means with the snubbing means for maintaining the clamping relation of the same.

7. An anchor connector of the class described, comprising a frame, wire snubbing means mounted on said frame for snubbing engagement with a wire to be anchored, and wire clamping means also mounted on said frame at one end of said snubbing means, said snubbing means and clamping means being relatively movable on said frame towards and away from each other and being adapted to receive the wire therebetween for clamping engagement therewith, and means for interlocking the clamping means with the snubbing means for maintaining the clamping relation of the same, said snubbing means being also pivotal on said frame for swinging movements about an axis parallel to the direction of relative movements of the snubbing means and clamping means.

8. An anchor connector of the class described, comprising a frame, wire snubbing means mounted on said frame for snubbing engagement with a wire to be anchored, and wire clamping means 25 also mounted on said frame at one end of said snubbing means, said snubbing means and clamping means being relatively movable on said frame towards and away from each other and being adapted to receive the wire therebetween for 30 clamping engagement therewith, and means for interlocking the clamping means with the snubbing means for maintaining the clamping relation of the same, said snubbing means being also pivotal on said frame for swinging movements 35 about an axis parallel to the direction of relative movements of the snubbing means and clamping means, and said means for interlocking the clamping means with the snubbing means being effective responsive to swinging movement 40 of the snubbing means in one direction about its pivotal axis, and being ineffective responsive to swinging movement in the opposite direction.
